(57)

The ornamental design for a cord wrap and organizer, as shown and described.

DESCRIPTION

FIG. 1 is a top-front perspective view of a cord wrap and organizer showing our new design;

FIG. 2 is a bottom-front perspective view of the cord wrap and organizer of FIG. 1;

FIG. 3 is a top-rear perspective view of the cord wrap and organizer of FIG. 1;

FIG. 4 is a bottom-rear perspective view of the cord wrap and organizer of FIG. 1;

FIG. 5 is a top plan view of the cord wrap and organizer of FIG. 1;

FIG. 6 is a bottom plan view of the cord wrap and organizer of FIG. 1;

FIG. 7 is a front end elevation of the cord wrap and organizer of FIG. 1;

FIG. 8 is a rear end elevation of the cord wrap and organizer of FIG. 1;

FIG. 9 is a left side elevation of the cord wrap and organizer of FIG. 1;

FIG. 10 is a right side elevation of the cord wrap and organizer of FIG. 1; and,

FIG. 11 is a perspective view of the cord wrap and organizer, shown reduced in scale in an exemplary operating environment.

In the drawings, the broken lines depict environmental subject matter only and form no part of the claimed design.

(57) **CLAIM**

The ornamental design for a cord wrap and organizer, as shown and described.

DESCRIPTION

FIG. 1 is a top-front perspective view of a cord wrap and organizer showing our new design;

FIG. 2 is a bottom-front perspective view of the cord wrap and organizer of FIG. 1;

FIG. 3 is a top-rear perspective view of the cord wrap and organizer of FIG. 1;

FIG. 4 is a bottom-rear perspective view of the cord wrap and organizer of FIG. 1;

FIG. 5 is a top plan view of the cord wrap and organizer of FIG. 1;

FIG. 6 is a bottom plan view of the cord wrap and organizer of FIG. 1;

FIG. 7 is a front end elevation of the cord wrap and organizer of FIG. 1;

FIG. 8 is a rear end elevation of the cord wrap and organizer of FIG. 1;

FIG. 9 is a left side elevation of the cord wrap and organizer of FIG. 1;

FIG. 10 is a right side elevation of the cord wrap and organizer of FIG. 1; and,

FIG. 11 is a perspective view of the cord wrap and organizer, shown reduced in scale in an exemplary operating environment.

In the drawings, the broken lines depict environmental subject matter only and form no part of the claimed design.
